UNITED STATES PATENT OFFICE.

CORWILL JACKSON, OF CHICAGO, ILLINOIS.

RAILWAY-ROADBED WORKING TOOL.

Application filed December 29, 1924. Serial No. 758,659.

To all whom it may concern:

Be it known that I, CORWILL JACKSON, a citizen of the United States, residing at Chicago, county of Cook, State of Illinois, have invented certain new and useful Improvements in Railway-Roadbed Working Tools, of which the following is a specification.

This invention relates to improvements in railway road bed working tools.

The main objects of this invention are:

First, to provide an improved machine for loosening and removing the ballast from railway road beds.

Second, to provide a machine of this character in which the ballast between the ties is rapidly loosened and removed to the side of the road bed.

Third, to provide a machine of this character which is very simple in structure and operation.

Objects pertaining to details and economies of construction and operation of my improved machine will definitely appear from the detailed description to follow.

I accomplish the objects of my invention by the devices and means described in the following specification. The invention is clearly defined and pointed out in the claims.

A structure embodying the features of my invention is clearly illustrated in the accompanying drawing forming a part of this application, in which:

Fig. I is a fragmentary view partially in vertical section of a machine embodying the features of my invention, only such parts being illustrated as are deemed necessary to illustrate the invention.

Fig. II is a fragmentary side elevation.

Fig. III is a perspective view of a portion of the drop hammer or crosshead with one of the tools thereon.

In the drawing similar reference numerals indicate similar parts in all of the views.

Referring to the drawing, 1 represents the ties of a railway track and 2 the rails thereof. My machine in the embodiment illustrated comprises a frame 3 adapted as a truck body provided with carrying wheels 4 adapted to travel upon a railway track. This frame has upright ways 5 in which the crosshead or drop hammer 6 is reciprocatingly mounted.

The means for lifting the crosshead comprises the chains 7. The means for driving the chains is not illustrated as this forms no

part of this invention. A suitable driving means, however, is illustrated in my application for Letters Patent Serial No. 758,658 filed concurrently herewith. The crosshead is lifted by this actuating means and allowed to drop, acting as a drop hammer.

The crosshead has recesses 8 on its under side positioned to receive the rails of the track as indicated by dotted lines in Fig. I.

The crosshead has a plurality of tools 10 mounted thereon in two sets or groups, in the structure illustrated there being three tools in each set and the tools of each set facing in opposite directions. These tools are pivoted at 11, the pivots being disposed longitudinally of the truck so that they are free to swing laterally, all the tools of a set swinging in the same direction.

The tools have pointed tips 12 with shoulders 13 in spaced relation to the ends of the tips. These tips are laterally directed, the tools being forwardly curved so that when the tools come in contact with the roadbed they tend to swing forwardly, striking the roadbed, and carrying the loosened material outwardly from the center of the roadbed. The movement of the tools is indicated by dotted lines in Fig. I.

It is the practice in railway engineering at certain periods to remove and screen the ballast and replace it; also in realining or raising sections of the track it is necessary to remove more or less of the ballast between the ties. This may be quickly accomplished with my machine, the ballast being loosened and considerable portions of it moved to the sides of the road bed, very greatly lessening the amount of hand labor required.

I have illustrated and described my improvements in an embodiment which I have found very practical. I have not attempted to illustrate or describe certain embodiments or adaptations which I contemplate and I have shown only such parts of the machine as seem necessary to illustrate my improvements as it is believed that the disclosure made will enable those skilled in the art to embody or adapt my improvements as may be desired.

Having thus described my invention what I claim as new and desire to secure by Letters Patent is:

1. In a machine of the class described, the combination of a truck adapted to travel upon a railway track, vertical ways on said

- truck, a crosshead constituting a drop hammer reciprocatingly mounted on said ways and recessed on its under side to receive the rails of the track, means for actuating said crosshead, and tools pivotally mounted on said crosshead in opposed laterally facing sets, the tool pivots being disposed longitudinally of the truck, there being a plurality of tools in each set, said tools having laterally directed points so that the tools tend to swing laterally upon contacting with the ballast of a track, said tools having forwardly facing shoulders spaced from their tips.
15. 2. In a machine of the class described, the combination of a truck adapted to travel upon a railway track, vertical ways on said truck, a crosshead constituting a drop hammer reciprocatingly mounted on said ways and recessed on its under side to receive the rails of the track, means for actuating said crosshead, and tools pivotally mounted on said crosshead in opposed laterally facing sets, the tool pivots being disposed longitudinally of the truck, there being a plurality of tools in each set, said tools having laterally directed ends so that the tools tend to swing laterally upon contacting with the ballast of a track.
20. 3. In a machine of the class described, the combination of a truck adapted to travel upon a railway track, vertical ways on said truck, a crosshead constituting a drop hammer reciprocatingly mounted on said ways, means for actuating said crosshead, and tools pivotally mounted on said crosshead to swing laterally of the track, said tools having laterally directed points so that the tools tend to swing laterally upon contacting with the ballast of a track, said tools having forwardly facing shoulders spaced from their tips.
25. 4. In a machine of the class described, the combination of a truck adapted to travel upon a railway track, vertical ways on said truck, a crosshead constituting a drop hammer reciprocatingly mounted on said ways, means for actuating said crosshead, and tools pivotally mounted on said crosshead to swing laterally of the track, said tools having laterally directed ends so that the tools tend to swing laterally upon contacting with the ballast of the track.
30. 5. In a machine of the class described, the combination with a railway truck, of a crosshead reciprocatingly mounted thereon transversely of the track upon which the truck is traveling, and a plurality of tools pivotally mounted on said crosshead to swing laterally of the track on which the truck is traveling, said tools having laterally directed points and forwardly facing shoulders spaced from their tips.
35. 6. In a machine of the class described, the combination with a railway truck, of a

crosshead reciprocatingly mounted thereon transversely of the track upon which the truck is traveling, and a plurality of tools pivotally mounted on said crosshead to swing laterally of the track on which the truck is traveling.

7. In a machine of the class described, the combination of a railway truck, a drop hammer reciprocatingly mounted thereon, and a plurality of tools pivotally mounted on said drop hammer to swing in a plane transverse to the plane of the track on which the truck is traveling.

8. In a machine of the class described, the combination of a railway truck, a drop hammer member reciprocatingly mounted thereon, and a tool pivotally mounted on said drop hammer member to swing in a plane transverse to the plane of the track on which the truck is traveling upon coming into contact with the material worked upon.

9. In a machine of the class described, the combination of a drop hammer, actuating means therefor, and tools pivotally mounted on said drop hammer in opposed laterally facing groups, there being a plurality of tools in each set, said tools having laterally directed points so that the tools tend to swing laterally upon contacting with the material worked upon, said tools having forwardly facing shoulders spaced from their tips.

10. In a machine of the class described, the combination of a drop hammer, actuating means therefor, and tools pivotally mounted on said drop hammer in opposed laterally facing groups, there being a plurality of tools in each set, said tools having laterally directed ends so that the tools tend to swing laterally upon contacting with the material worked upon.

11. In a machine of the class described, the combination of a drop hammer, actuating means therefor, and a series of tools pivotally mounted on said drop hammer to face in the same direction, said tools having laterally directed ends so that they tend to swing upon coming into contact with the material worked upon.

12. In a machine of the class described, the combination of a drop hammer, actuating means therefor, and a plurality of tools pivotally mounted on said drop hammer to face in the same direction and to swing in the same direction one behind another.

13. In a machine of the class described, the combination of a drop hammer, and a plurality of tools pivotally mounted on said drop hammer to swing in the same direction, said tools having forwardly directed points and forwardly facing shoulders spaced from their tips.

14. In a machine of the class described, the combination of a drop hammer member, and a plurality of tools pivotally mounted

on said drop hammer member to swing laterally, said tools having laterally directed points and forwardly facing shoulders spaced from their tips.

5 15. In a machine of the class described, the combination of a drop hammer, and a tool pivotally mounted on said drop hammer, said tool having a forwardly directed point and a forwardly facing shoulder spaced from its tip.

10 16. In a machine of the class described, the combination of a railway truck, a drop hammer reciprocatingly mounted thereon, and a plurality of tools pivotally mounted 15 on said drop hammer one behind another for free swinging movement from an approximately vertical position toward a horizontal position in a plane transverse to the plane of the track on which the truck is traveling, 20 the tools having laterally directed ends to facilitate such swinging movement upon contacting with the material worked upon, said tools having forwardly facing shoulders spaced from their tips.

25 17. In a machine of the class described,

the combination of a railway truck, a drop hammer reciprocatingly mounted thereon, and a plurality of tools pivotally mounted on said drop hammer one behind another for free swinging movement from an approximately vertical position toward a horizontal position in a plane transverse to the plane of the track on which the truck is traveling, the tools having laterally directed ends to facilitate such swinging movement 30 upon contacting with the material worked upon. 35

18. In a machine of the class described, the combination of a railway truck, a drop hammer reciprocatingly mounted thereon, and a plurality of tools pivotally mounted on said drop hammer one behind another for free swinging movement from an approximately vertical position toward a horizontal position in a plane transverse to the 40 plane of the track on which the truck is traveling.

In witness whereof I have hereunto set my hand.

CORWILL JACKSON.
